JOHANN GUSTAV BURCHARTZ, OF COLOGNE, GERMANY.

CARBURETER.

1,079,634.

Specification of Letters Patent. Patented Nov. 25, 1913.

Application filed July 26, 1912. Serial No. 711,611.

To all whom it may concern:

Be it known that I, JOHANN GUSTAV BURCHARTZ, a subject of the King of Prussia, and residing at Cologne, in the Province of the Rhine, Kingdom of Prussia, German Empire, have invented certain new and useful Spray-Carbureters for Internal-Combustion Engines, of which the following is a specification.

10 This invention relates to spray carbureters for internal combustion engines, in which the composition of the gas mixture which is composed of air and a liquid fuel, is automatically regulated without the aid of auxiliary air passages, auxiliary air valves, or similar mechanical equivalents, however great the speed of the motor may be.

15 The object of the present invention is to supply fuel to the motor with a uniform area of air passage, and consequently without the aid of auxiliary air, to supply exactly the requisite quantity of fuel for various speeds and loads.

20 In the accompanying drawings Figure 1 shows a longitudinal section of the carbureter, and Fig. 2 shows a horizontal section on the line A—B, of Fig. 1.

25 At *a*, the fuel passes into the float casing, in which it is kept at a constant height in the well known manner. Through the pipe *b* the fuel flows into the chamber *c* and through the openings *d*, *e*, into an injection duct *g* and a fuel container *f*. When the motor is not running, the level of the fuel 30 takes the height *h*—*i* determined by the float. The injection duct *g* has its opening *k*, disposed at a considerably higher level than that of the liquid fuel. The round damper *l* which controls the gas mixture has 35 a slot *m* which may be closed by a screw plug *n*, and when the damper is almost closed only a predetermined very narrow opening remains above the opening *k*. The interstice between the opening *k* and the 40 damper *l* is so small that the vacuum and the speed of the air which prevails in the narrowest section, can act in full force on the opening *k* and take from it sufficient fuel for a certain speed of the motor, for instance, for a given number of rotations 45 when running light. The gas mixture in this case flows through the slots *z*, in the damper, to the engine suction pipe.

50 The fuel container *f* with the supply inlet *d* and the outlet are primarily influenced on opening the damper *l* by the vacuum of

the suction tube. When running light, the vacuum and the flow of the air in the vicinity of the opening *f*, *g*, are so small, that no material quantity of fuel is carried away with the air current. If the round damper is opened more, then the fuel container *f* takes part in the supply of the fuel. When the damper is fully opened and the heavily loaded motor is running slow, then the level of the fuel in the container will stand fairly high, so that a larger quantity of fuel particles can be carried away through the openings *g*. The outflow from the injection duct *g* has not increased in the same proportion on the transfer from running light to the full load, because the sectional area of the flow at the outlet opening *k*, has largely increased. As soon as the speed of rotation of the motor and the vacuum of the suction pipe have increased further, there may be seen a sinking of the column of fuel in the container *f*, and the fuel no longer escapes from the openings *g* in streams, but in the form of separate particles, which are in course of evaporation. On further increase in the speed of rotation of the motor and consequently of the aspiration in the aspiration tube, the level of the fuel sinks deeper still in the container *f*, and the separate drops of fuel are continuously smaller. The space between the level of the fuel and the outlet opening *g*, is then mostly filled with the vapor of the fuel. In general therefore on the increase of vacuum and flow of air there will flow from the opening *g* a quantity of fuel which increases more slowly than if a simple injection duct of the ordinary kind were used. The determining feature for the quantity of outflow is, in the first place, the sectional area of the opening *d*; but some importance is possessed by the openings *g*, the sum of the sectional areas of which amounts to a multiple of the opening *d*. Flow of fuel from the openings *g* will not take place on the cessation of the aspiration in the suction tube for at this moment no rising of the separate particles of the fuel, which has sunk down to the line *h*—*i*, in the container *f*, can take place.

Owing to the arrangement of the duct and the mode of action of the container *f*, with the inlet opening *d* lying below, and the outlet opening *g*, it follows that there is always supplied to the motor a quantity of fuel which is proportional to the aspirated air. In order that this may take place in the

rapid change from a very small to a very high number of rotations, the following arrangement is adopted: At the head of the fuel container *f* is provided a space *y* which lies around the outlet opening *q* and higher than the normal level of the fuel. In this space there collects a certain supply of fuel, which on the sudden transfer to a very high speed of rotation supplies the first increased demand for fuel. It is moreover necessary that on the sudden opening of the damper, that is, on the passage from very small to very high motor speed, or from smaller to greater loading the fuel should flow from the opening *q* in a closed stream. Without the container *y*, this would not be possible, because the fuel flowing through the various openings *q*, in a closed stream would present a larger quantity than that which can enter through the lower opening *d* at this moment into the container *f*. As however, the quantity of fuel which is in the container *f*, forms a reserve and can flow off without having to enter through the opening *d* into the container *f*, it is obvious that this quantity of fuel collected in the space *y* will flow off or be drawn up through the opening *q* in closed streams, because the container *y* is emptied of air through the openings *x*. The fuel, consequently, as soon as the damper is fully opened, will pass through the openings *q* under the vacuum effect thus created, in order to be evaporated and mixed with air to reach the motor.

The openings *x*, the areas of which are considerably smaller than that of the openings *q*, have, as already indicated the object of causing a removal of air from the space *y* when the fluid fuel in the container *f* rises, and consequently to admit of the filling of this space with fluid fuel. This fuel will not escape through the opening *x* on the sudden opening of the round damper, but, as already stated will take its course through the opening *q*, because on the one hand, the openings *q* being placed at the outer edge of

the head of the container *f* are exposed to a stronger suction through the closely passing air current; and on the other hand the vacuum will not be felt through the small area of the openings *x*, because of the much greater area of the openings *q*. When, on the increased number of rotations and under the conditions above set forth, the level of the liquid fuel in the container *f* sinks again, then evaporated fuel can also pass away without injury through the openings *x*.

Having now described my invention and in what manner the same is to be operated, what I claim is—

1. In an injection carbureter for internal combustion engines an injection duct *g* having an outlet *k* lying considerably above the level of the fuel close to a slot *m* of the throttling organ *l*, a fuel container *f* having supply openings *q* on the level of the fuel, an inlet opening smaller than the said supply openings *q*, and a store space *y* at the head of the fuel container *f* around and above the supply openings *q* as set forth. 60

2. In an injection carbureter for internal combustion engines an injection duct *g* having an outlet *k* lying considerably above the level of the fuel close to the slot *m* of the throttling organ *l*, a fuel container *f* having supply openings *q* on the level of the fuel an inlet opening smaller than the said supply openings *q*, and a store space *y* at the head of the fuel container *f* around and above the supply openings *q* the said space 70 *y* being provided with air discharging openings the sectional area of which is considerably smaller than that of the supply openings, as set forth. 80

In testimony, whereof I have signed my name to, this specification in the presence of two subscribing witnesses.

JOHANN GUSTAV BURCHARTZ.
